UNITED STATES PATENT OFFICE.

HARRY FRIEDMAN, OF TIFFIN, OHIO.

INDICATOR.

Application filed July 24, 1924. Serial No. 728,037.

To all whom it may concern:

Be it known that I, HARRY FRIEDMAN, a citizen of the United States, and a resident of Tiffin, in the county of Seneca and State of Ohio, have invented a new and useful Indicator, which invention is fully described in the following specification.

My invention has for its object to provide an indicating means for indicating any conditions that may arise in connection with any combination of circumstances, as in games or ideas of fact or imagination, and which may be numerically or alphabetically designated or designated by any other indicia or set phrases.

The invention may be contained in structures of different forms. To illustrate a practical application of the invention I have selected a structure containing the invention and shall describe it hereinafter. The structure selected for purposes of illustration is shown in the accompanying drawings.

Figure 1 of the drawings is a top view of the device containing my invention. Figure 2 is an end view and Figure 3 is a broken view of a disc, on which may be printed or written suitable indicating or designating terms or numbers or phrases.

The device shown in the drawing is supported on the table 1. It is provided with a ring 2 of iron that is mounted in spaced relation with respect to the table top by means of the blocks or legs 3. The battery 4, that may be formed of dry cells 5 of the type well known in the art, is connected to a wire 6 that is supported on posts 7. The posts 7 may be formed of electricity conducting material such as metal, while the table top 8 may be formed of wood or fibre or other suitable material that will operate to insulate the posts 7. The posts 7 are also connected to the blocks or legs 3 by means of wires 9. The blocks 3 are also formed of electricity conducting material and consequently the iron ring 2 is connected at a plurality of points to the wire 6 that connects the posts 7, which are located in the corners of the table 1. The table top 8 is preferably square in form and the diameter of the ring 2 is substantially the same as the width or length of the table, and so that portions of the wire 6 located between the posts 7 will be located partly without the outer cylindrical surface of the ring to within, substantially, the inner cylindrical surface of the ring. The posts, however, support the wire so that it lies

slightly below the ring and does not make contact therewith. The wire 6, however, is connected to the ring through the posts 7, the wires 9 and the blocks 3. When an electric current passes through the wires 6, it produces a slight magnetic field in the iron ring that varies at different points along the ring, because of the difference in the relative positions between the parts of the ring and portions of the wire. The ring being formed of iron, and although it is of considerable size, produces considerable resistance to the flow of the current through the ring itself instead of through portions of the wire 6. The wire 6 is formed of copper and is comparatively a large wire and consequently has a low resistance, a much lower resistance than that of the ring 2.

A rotatable member 10 may be pivotally supported by means of a spindle 11 that is located in the center of the ring 2. The member 10 is provided with an electromagnet 12 having projecting legs 13 that are surrounded by the coil 14 and so as to produce the same polarity in the ends of the legs 13. If desired, the magnet 12 may be formed horseshoe shaped, and the coil 14 secured about the magnet. If the core of the magnet is made horseshoe shaped it may be supported on the rotatable member 10 so that the legs 13 will be located on opposite sides of the ring 2, that is, one will be located on the inside of the ring and the other will be located on the outside. The rotatable member may be loaded by means of suitable metal, such as by means of the plate or block 15, in order to counterbalance the weight of the magnet 12.

The coil 14 of the magnet 12 is connected to the spindle 11 by means of the wire 16, and the spindle is connected to the battery 4 by means of the wire 17. Also, the coil 14 is connected to a spring contact 18 that may be secured to one of the legs 13 of the magnet and which makes sliding contact with the ring 2. Thus a branch circuit of variable resistance is formed between the terminals of the battery 4 as the member 10 is rotated on the spindle 11. This produces a varying current through the coil 14 and produces a variable magnetic drag between the ring 2 and the magnet 12. This magnetic drag also is varied by the change in relation between portions of the ring 2 and portions of the wire 6, which produces slight variation in the field induced in the

ring 2, which to a corresponding degree will affect the magnetic drag on the magnet 12. This variation of the magnetic drag on the magnet 12 will affect the rotation of the member 10 when the member 10 is caused to whirl. Also as the contact 18 is moved over the surface of the ring 2, it approaches and recedes from the points at which the ring is connected with the wire 6, and consequently the intensity of current that passes through the coil 14 will vary, which will vary the magnetism of the legs 13 of the magnet. This variable drag between the ring 2 and the magnet 12 will produce unexpected results when the rate of rotation of the member 10 becomes very slow, and will bring the rotatable member at unexpected positions of rest or unexpected stationary positions. In order to produce a pronounced local field, an electromagnet 20 may be located in the circuit of the wire 6. If desired, this magnet may be constructed substantially the same as the magnet 12, it being provided with a coil 21 that is connected to the battery 4 by the wire 22 and the wire 6.

The relative positions for starting the rotation of the member 10 or for designating its positions of rest after rotations of the member, may be made more definite by the use of a disc 24 having lines thereon to subdivide it into sectors. The sectors may be designated by any suitable members or other indicia or phrases, according to the use to which the invention is to be put, that is, the sectors may be designated by the names of the different cards of a deck or by letters, or each sector may receive a particular instruction or supposed information. The designating indicia or the markings and phrases used in the sectors may be varied as desired. In order to more definitely indicate the position of the rotatable member when at rest, the plate 15 may be marked or grooved along the line 26. This may be sighted with reference to division lines of the disc 24 by the eye, to determine more exactly the relative position of the rotatable member 10 as at the completion of rotation of the member 10 when it comes to a point of rest.

I claim:—

1. In an indicator, a ring of magnetic material, a rotatable member, a magnet supported on the rotatable member and in magnetic relation to the ring, and means for producing a variable field along the ring.

2. In an indicator, a ring of magnetic ma-

terial, a rotatable member, a magnet supported on the rotatable member and in magnetic relation to the ring, and means for producing a variable field in the magnet. 60

3. In an indicator, a ring of magnetic material, a rotatable member, a magnet supported on the rotatable member and in magnetic relation to the ring, means for producing a variable field along the ring, and means for producing a variable field in the magnet. 65

4. In an indicator, a table, a ring of magnetic material supported on the table, a source of electric current, a wire having portions extending in straight lines across portions of the ring and connected to the source of current, a rotatable member, a magnet supported on the rotatable member and having a coil connected to one terminal of the source of current and the other terminal connected to the ring, the ring connected to the wire at a plurality of points. 70

5. In an indicator, a ring of magnetic material, a rotatable member, a magnet supported on the rotatable member and in magnetic relation to the ring, and means for producing a variable field along the ring, a disc having designating characters located in subdivisions of the disc and positioned in indicative relation to the rotatable member. 85

6. In an indicator, a ring of magnetic material, a rotatable member, a magnet supported on the rotatable member and in magnetic relation to the ring, means for producing a variable field along the ring and means for producing a variable field in the magnet, a disc having designating characters located in subdivisions of the disc and positioned in indicative relation to the rotatable member. 90

7. In an indicator, a table, a ring of magnetic material supported on the table, a source of electric current, a wire having portions extending in straight lines across portions of the ring and connected to the source of current, a rotatable member, a magnet supported on the rotatable member and having a coil connected to one terminal of the source of current and the other terminal connected to the ring, the ring connected to the wire at a plurality of points, a disc having designating characters located in subdivisions of the disc and positioned in indicative relation to the rotatable member. 100

In testimony whereof I have hereunto signed my name to this specification:

HARRY FRIEDMAN.
